UNITED STATES PATENT OFFICE.

CALVIN B. PATCH, OF GLENELLYN, ILLINOIS, ASSIGNOR TO WILLIAM H. MINER, OF CHAZY, NEW YORK.

CAR-UNDERFRAMING.

1,186,679.

Specification of Letters Patent. Patented June 13, 1916.

Application filed July 12, 1915. Serial No. 39,276.

To all whom it may concern:

Be it known that I, CALVIN B. PATCH, a citizen of the United States, residing at Glenellyn, in the county of DuPage and State of Illinois, have invented a certain new and useful Improvement in Car-Underframing, of which the following is a full, clear, concise, and exact description, reference being had to the accompanying drawings, forming a part of this specification.

This invention relates to improvements in car underframing.

An object of the invention is to provide simple, cheap, and efficient means for rigidly connecting and bracing members of a car underframe, particularly the center sills, sub-sills and body bolster.

In the drawing forming a part of this specification, Figure 1 is a longitudinal, vertical, sectional view of a portion of a car underframe showing my improvement in connection therewith. Fig. 2 is a top plan view of the structure illustrated in Fig. 1, certain parts being broken away to more clearly illustrate the arrangement. And Fig. 3 is a vertical, sectional view taken substantially on the line 3-3 of Fig. 1.

In said drawing, 10-10 denote wooden center sills, 11 the end sill, 12 the buffer block and 13 the sub-sills, the outer ends of which terminate to the rear of the body bolster 14. Secured to the inner sides of the center sills 10-10 are strengthening and bracing channels 15-15, the latter extending rearwardly beyond the body bolster, as clearly illustrated in Fig. 1. At their forward ends, a tie strap 16 may be employed extending between the channels 15-15 and also bolted to the end sill 11. Draft sills 17 or plates 17 are riveted to the lower flanges of the channel 15-15, said draft members 17 being preferably of Z bar formation. The draw bar carry-iron is designated by the reference 18.

To rigidly connect and brace the various sills and bolster I have provided a member A preferably in the form of a casting. Said member A comprises a horizontal top web 19 recessed as indicated at 20 to thereby lighten it, a depending rear vertical wall 21, vertical side flanges 22-22 having upstanding portions 23 overlapping the outer faces of the center sills 10, horizontal rearwardly extending flanges 24 at the rear thereof forming pockets for the ends of the sub-

sills 13, and an overhanging lip or flange 25 at its forward end which rests upon and is supported by the top member of the body bolster. The member A is secured to the channels 15 by any suitable means such as 26-26.

To take up wear or horizontal play, shims 27-27 may be inserted in the pockets 24 at the ends of the sub-sills 13, said shims being held in place by any suitable means such as 28-28.

From the preceding description, it will be seen that the casting A is rigidly supported by means of the overhanging lip 25 and by being riveted to the lower flanges of the channels 15-15, the latter being supported by both the center sills to which they are secured and by the body bolster. The center sills 10 being confined between the channels 15 to which the casting A is riveted, and the upstanding flanges 23-23 of the casting A, are effectively prevented from lateral displacement. In addition to the foregoing the sub-sills are efficiently supported by the pockets 24 and longitudinal shocks 80 between the bolster and sub-sills are efficiently transmitted through the casting A.

Although I have herein shown and described what I now consider the preferred embodiment of my improvement, yet the same is merely illustrative and I contemplate all changes and modifications as come within the scope of the claims appended hereto.

I claim:

1. In car underframing the combination with a body bolster, center sills, and sub-sills, of a tying and supporting member located at the rear of the body bolster, said member having pockets to receive and help support the ends of the sub-sills and an overhanging projection supported on top of the body bolster. 90

2. In car underframing, the combination with a body bolster, center sills, flanged plates secured to the sides of said sills and sub-sills, of a casting at the rear of the body bolster having pockets to receive and help support the ends of said sub-sills and riveted to said flanged plates. 100

3. In car underframing, the combination with a body bolster, center sills, flanged plates secured to the sides of said sills and sub-sills, of a casting at the rear of the body bolster having pockets to receive the ends 110

of said sub-sills and riveted to said flanged plates, said casting having also a forwardly extended lip overhanging said bolster.

4. In car underframing, the combination 5 with a body bolster, wood center sills, channels secured to the inner faces of said sills and extending to the rear of the bolster, and sub-sills, of a supporting and bracing member, said member having shoulders at the 10 rear thereof against which the ends of said sub-sills are adapted to abut and provided also with a forwardly extended lip overhanging the body bolster, said member being riveted to the flanges of said channels.
- 15 5. In car underframing, the combination with a body bolster, wood center sills, channels secured to the inner faces of said sills and extending to the rear of the bolster, and sub-sills, of a supporting and bracing member, said member having shoulders at the rear 20 thereof against which the ends of said sub-sills are adapted to abut and provided also with a forwardly extended lip overhanging

the body bolster, said member being riveted to the flanges of said channels, and having 25 also upstanding flanges along its outer edges overlapping the faces of said center sills.

6. In car underframing, the combination 30 with a body bolster, wood center sills, plates secured to the inner faces of said sills and extending to the rear of the bolster, and sub-sills, of a supporting and bracing member having pockets at the rear end thereof in which the ends of said sub-sills are adapted to be received and supported, said member 35 being also provided with a forward extension overhanging the body bolster, said member having also upstanding, longitudinally extending flanges along its outer edges overlapping the outer faces of said center sills 40 and thereby adapted to prevent spreading of the latter.

In witness that I claim the foregoing I have hereunto subscribed my name this 6th day of July, 1915.

CALVIN B. PATCH.
